Primary Examiner — John Windmuller(74) *Attorney, Agent, or Firm* — Keisling & Pieper PLC;
David B. Pieper; Trent C. Keisling**CLAIM**

The ornamental design for an adjustable groove masonry clamp, as shown and described.

DESCRIPTION

FIG. 1 is a perspective view of an adjustable groove masonry clamp showing my new design in an expanded position;

FIG. 2 is another perspective view thereof;

FIG. 3 is a left side view thereof;

FIG. 4 is a right side view thereof; and,

FIG. 5 is a front view thereof;

FIG. 6 is a back view thereof;

FIG. 7 is a top view thereof; and

FIG. 8 is a bottom perspective view thereof; and

FIG. 9 is another perspective view thereof showing a compacted position of the adjustable cleat.

FIG. 10 is another perspective view thereof;

FIG. 11 is a left side view thereof;

FIG. 12 is another perspective view thereof showing a rotated and compacted position of the adjustable cleat.

FIG. 13 is another perspective view thereof;

FIG. 14 is a left side view thereof; and,

FIG. 15 is an exploded view of the assembly visible during position changes.
